UNITED STATES PATENT OFFICE.

HARRY LANDSIEDEL, OF NORWOOD, OHIO, ASSIGNEE TO THE DALTON ADDING MACHINE COMPANY, OF CINCINNATI, OHIO, A CORPORATION OF OHIO.

ADDING MACHINE.

Application filed May 25, 1921. Serial No. 472,390.

To all whom it may concern:

Be it known that I, HARRY LANDSIEDEL, a citizen of the United States, residing at Norwood, Hamilton County, and State of Ohio, have invented a new and useful Adding Machine, of which the following is a specification.

This invention relates to adding machines. It is well known that adding and calculating machines have been, and now are, provided with connections for operation by motor and have also been provided with hand levers for manual operation. To avoid confusion and preventing unnecessary operation and movement of parts whose operation is not needed, it is desirable to prevent operation of the hand lever when a machine is operated by motor. On the other hand, when a machine is being operated by hand, it is desirable to prevent operation thereof by the motor.

My present invention has special reference to mechanism for obtaining these results, and an object of the invention is to provide improved and effective means for preventing movement of the hand-lever when the machine is operatively connected with the motor, and to prevent operation of the motor control connections when the machine is adjusted for operation by the hand lever.

Another object of the invention is to provide means for disabling the full-stroke device when the machine is operatively connected with the motor and for enabling the full-stroke device to function when the machine is placed under control of the hand lever and the motor controlling connections are disabled.

There are other objects and advantageous results to be obtained, all of which will appear from the following description, reference being made to the drawings, in which

Fig. 1 is a view showing the present invention embodied in a machine of the Dalton type and showing the parts in the positions they occupy when the machine is under control of the hand lever and the motor controlling connections are disabled.

Fig. 2 is a similar view showing the position of the parts when the machine is under control of the motor and when the hand lever is disabled.

Fig. 3 is a plan view of the present invention, showing the positions of the parts 55 as in Fig. 1.

The rock shaft 1 is the usual controlling shaft of the adding machine. When the machine is in use the shaft 1 is rocked forward and backward, and such rocking movements 60 may be imparted either by hand lever or by motor operated connections.

The hand lever or handle 2 is operatively connected with one end of the rock shaft 1 by a familiar clutch device whereby the shaft will be turned in a forward direction when the hand lever or handle is drawn forwardly; but which permits the shaft to be turned in a forward direction by the motor while the handle remains stationary. This 70 clutch device is well known and is not shown in detail.

When the machine is operated by use of the hand-lever or handle 2, a full stroke device is needed so that the shaft 1 must be 75 turned far enough at each operation to permit or to cause proper operation of the machine. The full stroke device shown comprises a segmental arm 3, attached to the rock shaft and provided in its outer end with a number of notches 4 to be engaged by the end of a swinging detent or abutment 5 to prevent reverse movement of the shaft between the ends of any turning movement thereof in either direction. 85

The swinging detent or abutment 5 swings on a support 6, and is connected with a spring 7. When the shaft 1 is turned in a forward direction, the segmental arm 3 swings the lower end of the detent 5 forwardly. The lower end of the detent 5 continues to ride upon the notched outer end of the arm 3 until said arm passes beyond the lower end of the detent. Backward movement of the arm 3, prior to the completion of its forward movement, and until said arm 3 passes beyond and out of engagement with the detent 5, will be prevented by engagement of the detent 5 in the notches 4. After the shaft 1 has completed its forward turning movement and after the arm 3 has passed the detent 5, the shaft may return to its starting position. During backward turning of the shaft, the detent 5 rides upon the outer end of the arm 3 and prevents reverse or forward turning movement of the 100 105

shaft until the backward turning movement thereof is completed.

A lever 8 is pivotally supported by the shaft 1. The rear end of the lever 8 engages behind a stud 9, extending from an arm 10 that is rigid with the shaft 1. The forward end of the lever 8 has an anti-friction roller 11 engaged by a motor driven arm or lever 12. Backward movement of the lever arm 12 will turn the shaft 1 in a forward direction to the full extent required, but return movement of the lever 12 permits the shaft 1 to be returned to its starting point in the usual manner. The lever arm 12 is operated by the usual connections from a motor 13. The motor 13 is of the usual constantly running type, and the connections for operating the lever 12 from the motor are of the familiar arrangement, leaving the lever 12 normally disconnected from said connections so that said lever is only operated by the motor under control of manipulated devices provided for that purpose.

The connections for operating the lever 12 from the motor are enclosed within a casing 14 and may be of the type disclosed in my prior Patents, No. 1,209,838, dated Dec. 26, 1916, and No. 1,270,845, dated July 2, 1918. For present purposes it is sufficient to mention that the operation of the lever 12 by the motor connections that are housed within the casing 14 is under control of a movable part 15. In the embodiment of the invention shown, the parts 15 is in the form of an arm or lever to which one end of a link 16 is connected. The forward end of the link 16 is connected with an arm 17, secured to a rock shaft 18 so that a rocking movement imparted to the shaft 18 will engage and release the connections within the casing 14 by which the lever 12 is operated.

A bar 19 is supported upon arms 20, attached to a shaft 21. The bar 19 constitutes a key for controlling the motor connections and, as shown, is conveniently supported near the keyboard of the machine. Pressure upon the bar 19 will turn the shaft 21 in a forward direction. A lever 22 on the shaft 21 extends over an arm 23 on the shaft 18. By these connections the shaft 18 is turned to actuate the link 16 as required, to engage and to disengage the connections within the casing 14, that operate the lever 12.

My invention comprises devices for preventing operation of the hand lever or handle 2 and for disabling the full stroke device when it is intended to operate the machine with the motor; and my invention also comprises means for preventing operation of the lever 12 by preventing operation of the devices for engaging and releasing the operating connections for said lever, when it is intended to operate the machine by hand instead of by motor.

In the position of the parts shown in Fig. 1, the machine is adjusted for operation by hand and the motor control connections are locked against operation. An arm 24 attached to the shaft 21 extends upwardly. A detent device 25 is pivoted upon a support 26 and is provided with a shoulder 27 which, in the depressed or lowered position of the detent device shown in Fig. 1, constitutes an abutment for the arm 24, so as to prevent operation of the motor controlling key 19. However, if the detent device 25 be raised to the position shown in Fig. 2, the shoulder 27 is out of the way of the arm 24, leaving the motor control connections operative by the key 19. A spring 28, having one end attached to the forward end of the detent device 25 and its opposite end attached to a stationary part of the machine, constitutes an actuator for the detent device to raise the shoulder 27 thereof above the arm 24.

A slide 29 is operative on supports 30, extent of movement of the slide being limited to the length of the slots 31 through which the supports 30 extend. A projection 32 on the slide supports a roll 33, riding upon the upper edge of the detent device 25. In the forward position of the slide 29, the roll 33 latches within a notch 34 in the detent device and holds the detent in the depressed position shown in Fig. 1, in which the shoulder 27 constitutes an abutment for the arm 24. In the rear position of the slide 29 the roll 33 latches within a notch 35 in the detent device 25, and permits the spring 28 to raise the shoulder 27 above and out of the way of the arm 24. A finger piece or knob 36 on the sliding plate 29 extends through a slot in the machine case and constitutes means for moving the sliding plate 29 from one position to another.

The devices for preventing operation of the hand lever or handle 2 are also under control of the plate 29. In the forward position of the sliding plate 29, the motor is disabled and the machine is placed under control of the hand lever or handle. While in the rear position of the sliding plate 29 the hand lever or handle 2 is locked against operation and the machine is placed under control of the motor.

A link 37 has its forward end pivotally connected with the sliding plate 29. Said link is provided with a slot 38, receiving a supporting pin 39, permitting sliding movements of the link. The rear portion of the link 37 comprises a cam part 40 operating under a pin or roll 41, carried on the upper end of a lever 42. Rearward movement of the link 37 will operate the lever 42 to move the lower end thereof forwardly to the position shown in Fig. 2; while forward movement of the link 37 permits the lower end of the lever 42 to swing rearwardly to the position shown in Fig. 1. The hand lever or

handle 2 is in connection with an arm 43, having a pin or projection 44 extending therefrom. When the lower end of the lever 42 is swung forwardly by the rearward movement 5 of the slide 39, the lower end of the lever 42 is placed above the pin 44, thereby preventing a complete forward movement of the hand lever or handle 2. When the lower end of the lever 42 swings rearwardly, as in 10 Fig. 1, it is out of the way of the pin 44, leaving the hand lever or handle 2 operative, while the motor connections are inoperative.

Rearward movement of the link 37 also disables the full stroke device. As shown, the 15 detent 5 has a pin 45 which is engaged by the rear end of the link 37 during rearward movement of said link. Movement of the link 37 turns the detent 5 from the position shown in Fig. 1 to the position shown 20 in Fig. 2, leaving the segmental arm 3 free to operate without engaging the detent. When the link 37 is moved forwardly to place the machine under control of the operating lever 2 the spring 7 acts to return 25 the detent to the position shown in Fig. 1 in which the detent will ride upon the outer end of the segmental arm 3 when the shaft 1 is operated.

It is plain that the invention obtains all 30 of its intended objects in a highly convenient, efficient and satisfactory manner. The form of the invention may be widely varied without departure from the nature and principle thereof. I do not restrict myself 35 to unessential features, but what I claim and desire to secure by Letters Patent is:—

1. In a machine of the character described, the combination of a rock shaft, a motor for turning said shaft in one direction, devices controlling the operation of 40 said shaft by said motor, a hand lever having connection with said shaft for turning said shaft in the same direction that the motor turns it, and means settable while 45 said hand lever retains said connection with said shaft to prevent operation of said devices or said hand lever as desired.

2. In a machine of the character described, the combination with a part to be 50 operated, a motor for operating said part independently of the hand lever, and a hand lever for operating said part independently of the motor, of a device settable independently of said hand lever to prevent operation of said part by the motor when it 55 is desired to operate said part by the hand lever.

3. In a machine of the character described, the combination with a part to be 60 operated, a motor for operating said part independently of the hand lever, and a hand lever having connection with said part for operating said part independently of the motor, of a device settable while said hand 65 lever retains said connection with said part

to prevent operation of said part by the hand lever when it is desired to operate said part by the motor.

4. In a machine of the character described, the combination with a part to be 70 operated, a motor for operating said part independently of the hand lever, and a hand lever having connection with said part for operating said part independently of the motor, of a device settable while said hand 75 lever retains said connection with said part to prevent operation of said part by the hand lever when it is desired to operate said part by the motor, and vice versa.

5. In a machine of the character described, the combination with a motor, an element to be operated, connections controlling the intermittent operation of said element by the motor, and a hand lever having connection with said element for operating said element, of a part settable to prevent operation of said connections leaving the hand lever free to operate, a part settable while said hand lever retains said connection with said element to prevent operation of said hand lever leaving said connections free to operate, and a device independent of the hand lever controlling the setting of said parts for the purpose aforesaid.

6. In a machine of the character described, the combination of a motor, a lever arranged to be intermittently operated by the motor, connections controlling the intermittent operation of said lever by the 100 motor, a detent for preventing operation of said connections, a spring for moving said detent out of position to prevent operation of said connections, a manual device for moving said detent to position to prevent operation of said connections, and means for holding said manual device in position to hold said detent in position to prevent operation of said connections.

7. In a machine of the character described, 110 the combination of a rock shaft, a lever for turning said shaft in one direction and arranged to permit the shaft to be turned independently thereof while the lever remains stationary, an abutment movable to and from position to prevent movement of said lever, and means for moving said abutment to position to prevent operation of said lever.

8. In a machine of the character described, 115 the combination of a rock shaft, a power device for turning said shaft in one direction, a hand lever for turning said rock shaft in the same direction that it is turned by the power device, a full stroke device for said shaft preventing return turning movement 120 of the shaft until the handle is moved to full extent of movement, and means for disabling said full stroke device when the shaft is to be operated by the power device.

9. In a machine of the character described, 125

- the combination of a rock shaft, a power device for turning said shaft in one direction, a hand lever for turning said rock shaft in the same direction that it is turned by the power device, a full stroke device for said shaft preventing return turning movement of the shaft until the handle is moved to full extent of movement, and means for disabling said full stroke device and for preventing operation of said handle when the shaft is to be operated by the power device.
10. In a machine of the character described, the combination of a rock shaft, a lever for turning said shaft in one direction and arm ranged to permit the shaft to be turned independently thereof while the lever remains stationary, a full stroke device for said shaft preventing return turning movement of the shaft until the lever is moved to full extent of movement, and means for disabling said full stroke device and for locking said lever against operation.
11. In a machine of the character described, the combination of a rock shaft, a lever for turning said shaft in one direction and arranged to permit the shaft to be turned independently thereof while the lever remains stationary, a segmental arm attached to said shaft and having notches in the outer end thereof, a pivoted detent, a spring for holding said detent in position to ride upon the outer end of said arm during the turning movements of said shaft, and to engage in said notches for the purpose described, and a device for moving said detent to position in which it will not ride upon said arm or engage in said notches.
12. In a machine of the character described, the combination of a rock shaft, a lever for turning said shaft in one direction and arranged to permit the shaft to be turned independently thereof while the lever remains stationary, a segmental arm attached to said shaft and having notches in the outer end thereof, a pivoted detent, a spring for holding said detent in position to ride upon the outer end of said arm during the turning movements of said shaft, and to engage in said notches for the purpose described, and a device for moving said detent to position in which it will not ride upon said arm or engage in said notches for the purpose described, and a device for moving said detent to position in which it will not ride upon said arm or engage in said notches, and means controlled by said device for locking said lever against operation.
13. In a machine of the character described, the combination of a rock shaft, a lever for turning said shaft in one direction, power mechanism for operating said lever, connections for causing said power mechanism to operate said lever intermittently, an arm operated by said connections, a pivoted detent movable to and from position to prevent operation of said arm and thereby prevent operation of said connections, a spring for moving said detent to position to permit said arm to operate, and means for moving said detent in opposition to said spring to position to prevent operation of said arm and thereby prevent operation of said connections.
14. In a machine of the character described, a rock shaft, a lever for turning the rock shaft in one direction, an arm in connection with said lever, a pivoted abutment, and a device for moving said abutment to position to prevent movement of said arm and thereby prevent movement of said lever.
15. In a machine of the character described, the combination of a rock shaft, a hand lever for turning said shaft in one direction, a full stroke device arranged for the purpose described, means for disabling the full stroke device, and a motor for turning the shaft arranged to be operative when the full stroke device is disabled.
16. In a machine of the character described, the combination with a rock shaft, a lever for turning said shaft in one direction and arranged to permit the shaft to be turned independently thereof while the lever remains stationary, an abutment, means for moving said abutment to position to prevent complete movement of said lever, and means for moving said abutment to permit complete movement of said lever.

HARRY LANDSIEDEL.
